(57) CLAIM

The ornamental design for a soccer coaching board, as shown and described.

DESCRIPTION

FIG. 1 is a front perspective view of a soccer coaching board, according to the present invention;

FIG. 2 is a front elevation view of the soccer coaching board of FIG. 1;

FIG. 3 is a rear elevation view of the soccer coaching board of FIG. 1;

FIG. 4 is a right side elevation view of soccer coaching board of FIG. 1;

FIG. 5 is a left side elevation view of the soccer coaching board of FIG. 1;

FIG. 6 is a top plan view of the soccer coaching board of FIG. 1;

FIG. 7 is a bottom plan view of the soccer coaching board of FIG. 1; and,

FIG. 8 is a rear perspective view of the soccer coaching board of FIG. 1.

Thin consistent broken lines, where present, illustrate portions of the soccer coaching board that form no part of the claimed design. Thick broken lines segmenting the surface illustrate lines on the board and are a part of the claimed design.

1 Claim, 5 Drawing Sheets
